UNITED STATES PATENT OFFICE

104,287

DESIGN FOR A MUSICAL INSTRUMENT

Narciso S. Olayvar, Annapolis, Md.

Application February 9, 1937, Serial No. 67,538

Term of patent 7 years

To whom it may concern:

Be it known that I, Narciso S. Olayvar, a citizen of the Philippine Islands, and who has applied for citizenship of the United States, residing at Annapolis, in the county of Anne Arundel, and State of Maryland, have invented a new, original, and ornamental Design for a Musical Instrument, of which the following is a specification, reference being had to the accompanying drawing, forming part thereof.

I claim:

The ornamental design for a musical instrument, as shown

NARCISO S. OLAYVAR.
